CLAIM

The ornamental design for a support structure for grill, as shown and described.

DESCRIPTION

FIG. 1 is a perspective view of a support structure for grill; FIG. 2 is a front elevational view;

FIG. 3 is a rear side view;

FIG. 4 is a left side view;

FIG. 5 is a right side view;

FIG. 6 is a top plan view;

FIG. 7 is a bottom plan view;

FIG. 8 is a perspective view thereof in use;

FIG. 9 is a perspective view with the support structure in a collapsed position thereof in use; and,

FIG. 10 is another perspective view with the support structure in a collapsed position thereof in use.

The broken lines in the drawings represent environmental subject matter that form no part of the claimed design.
